UNITED STATES PATENT OFFICE.

GEORGE H. RUSSELL, OF FLORENCE, ALABAMA.

HOT-WATER FURNACE.

1,364,585.

Specification of Letters Patent.

Patented Jan. 4, 1921.

Application filed August 14, 1920. Serial No. 403,591.

To all whom it may concern:

Be it known that I, GEORGE H. RUSSELL, a citizen of the United States, residing at Florence, in the county of Lauderdale and State of Alabama, have invented a new and useful Hot-Water Furnace, of which the following is a specification.

This invention relates to furnace constructions, and more particularly furnaces of the 10 hot water type, the primary object being to provide a furnace of this character especially adapted for use in buildings of the bungalow type wherein the furnace may be positioned in one of the rooms of the main 15 floor of the building.

A further object of the invention is to provide a down draft furnace having hollow 20 grate bars, which grate bars provide water conduits, whereby the direct heat of the fire-beds is utilized for heating purposes.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without 30 departing from the spirit of the invention.

Referring to the drawings:—

Figure 1 illustrates a longitudinal sectional view through a furnace constructed in accordance with the present invention, and 35 showing the same as positioned within one of the walls of a building.

Fig. 2 illustrates a front elevational view of the same.

Fig. 3 illustrates a sectional view taken on 40 line 3—3 of Fig. 1.

Fig. 4 illustrates a sectional view taken on line 4—4 of Fig. 1.

Fig. 5 illustrates a sectional view taken on 45 line 5—5 of Fig. 1.

Fig. 6 illustrates a sectional view taken on line 6—6 of Fig. 1.

Referring to the drawings in detail, the reference character 5 designates the main firebox of the furnace which is disposed 50 above a lower firebox 6, the rear walls of the fireboxes being formed into a water back 7.

This water back 7 has communication with the hollow grate bars 8, at a point directly above the opening 9, which provides 55 a passageway for the smoke and products of combustion to pass from the fireboxes into

the smoke compartment 10, formed at the rear of the furnace, and which smoke compartment communicates with the flues 11 that carry the smoke to the chimney proper. 60

The lower grate bars 12 are also in communication with the water back 7 at the base thereof, and as shown this water back 7 also communicates with a radiator 13 disposed at the rear of the furnace, through the 65 upper pipe 14 and lower pipe 15 so that a complete circulation of water may be had between the water back 7 and radiator 13, it being understood however that the radiator 13 feeds a plurality of radiators which may 70 be disposed in the various rooms of the building.

The main firebox 5 is fed through the opening 16, which is closed by the door 17, the opening being formed in the forward 75 wall 18 of the furnace proper, at a point adjacent the upper extremity thereof, while the lower firebox 6 may be fed through the opening 19 also formed in the front wall 18 of the furnace, the latter opening being controlled by the door 20, it being the purpose of the invention however to supply the lower firebox 6 with fuel dropping from the main firebox 5. 80

As before stated, the furnace forming the 85 subject matter of this invention is of the down draft type, and to this end a plurality of openings 21 are formed in the upper portion of the furnace, which openings are controlled by means of the sliding plate 22, 90 which is also provided with openings whereby the down draft within the main firebox 5 may be regulated.

In order that the gas which might collect in the main firebox 5 may be carried off, an 95 exhaust pipe 23 is disposed within the main firebox 5, the upper extremity of the exhaust pipe 23 terminating at a point above the opening 16, to prevent coal being fed to the main firebox 5 from entering the exhaust 100 pipe 23, the lower extremity of the exhaust pipe 23 however terminating adjacent to the opening 9, whereby the gases will have an unobstructed passage through the smoke compartment 10. 105

Disposed above the main firebox 5 is a baking oven indicated by the reference character 24, which baking oven is provided with a door 25, to permit of easy access to the interior thereof. It might be further stated 110 however that an opening 26 is formed in the upper wall of the oven 24, which opening

may be closed by the pivoted door 27, to retain the heat in the oven, but if the oven is to be used as a broiler, it is obvious that the door 27 may be opened to permit smoke or 5 the like to pass from the oven and into the smoke compartment 10.

As shown, the rear wall of the furnace proper is spaced from the wall of the building in which the furnace is positioned, the 10 space being indicated by the reference character 28, which provides a compartment for the heat from the furnace to pass upwardly, and into the adjacent rooms, through the registers 29.

15 Supported under the lower grate bars 12 is an air intake pipe indicated at 30 which extends across the upper portion of the ash-pit, the inner extremity thereof lying within the combustion chamber 31 forming the 20 lower portion of the smoke compartment 10, the combustion chamber 31 being provided to accommodate accumulated gas which is consumed by the heat of the fires within the fireboxes.

25 Air is supplied to the fireboxes, through the opening 32, which is controlled by the hinged door 33, the air passing upwardly through the fireboxes in a well known manner.

30 While I have shown and described the furnace as designed for use on the main floor

of a building, it is to be understood that the furnace may be positioned in any suitable location, as for instance in the basement or cellar of a building.

35

What is claimed as new is:—

1. In a furnace construction, an upper firebox and a lower firebox, grate bars for each firebox, a water back disposed to the rear of the fireboxes, and forming the rear 40 walls thereof, a wall spaced from the water back to provide a smoke compartment, and said water back having an opening providing communication between the fireboxes and smoke compartment.

2. In a furnace construction, an upper firebox and a lower firebox, a water back forming the rear wall of the fireboxes, a wall spaced from the water back to provide a smoke compartment, said water back having an opening to provide communication between the fireboxes and smoke compartment, and an exhaust pipe disposed within the upper firebox and having its upper extremity located adjacent to the upper wall 55 of the upper firebox.

In testimony that I claim the foregoing as my own, I have hereto affixed my signature in the presence of a witness.

GEORGE H. RUSSELL.

Witness:

IVY E. SIMPSON.
